UNITED STATES PATENT OFFICE.

WILLIAM HEINZE, OF DARBY, PENNSYLVANIA.

FILM-REELING DEVICE.

1,217,598.

Specification of Letters Patent. Patented Feb. 27, 1917.

Application filed March 7, 1916. Serial No. 82,554.

To all whom it may concern:

Be it known that I, WILLIAM HEINZE, a citizen of the United States, residing at Darby, in the county of Delaware and State 5 of Pennsylvania, have invented certain new and useful Improvements in Film-Reeling Devices, of which the following is a specification.

This invention relates to reeling devices, 10 and particularly to mechanism for winding or reeling the film employed in connection with moving picture apparatus.

The primary object of the invention is to provide means whereby the re-winding of 15 picture film after the same has been run through the projecting apparatus, may be accomplished simultaneously with the operation of the picture projecting mechanism.

A further object of the invention is to provide means whereby the energy employed in 20 operating the picture projecting apparatus may be utilized to re-wind the film which may have been previously displayed.

A still further object of the invention is to provide simple and efficient means for 25 obviating the necessity of resorting to the additional function of re-winding picture film after it has been displayed before another film can be shown.

30 A still further and particular object of the invention is to provide a mechanism capable of application to any of the standard types of picture projecting apparatus, which is simple and inexpensive in construction, which is composed of but few simple and readily assembled parts, which parts are so arranged as to prevent the least possibility of the same becoming broken, worn, or deranged during operation, and which will 35 prove thoroughly practical and efficient for the purposes to which it is adapted.

With these objects in view, together with others which will appear as the description proceeds, the invention resides in the novel 40 combination and arrangement of parts, all as will be described more fully hereinafter, illustrated in the drawings and particularly pointed out in the claims.

The invention will be best understood by 45 reference to the accompanying drawings, wherein—

Figure 1 is a side elevation of a film reeling device constructed in accordance with my invention,—Fig. 2 is a vertical transverse section taken through the device,—Fig. 3 is a 50 fragmentary vertical section taken through

the casing for the device and illustrating the association of the film reels,—Fig. 4 is a sectional view taken on line 4—4 of Fig. 1,—and Fig. 5 is an enlarged fragmentary sectional view taken upon line 5—5 of Fig. 4.

As is well known to those more intimately associated with the art of exhibiting film to produce animated pictures, it is necessary after displaying each reel of film to re-wind 60 the same, in order that it may be reeled properly for further display. Ordinarily, for this purpose, separate machines or reeling devices are employed, although in some apparatus the film is reversed through the 65 projecting mechanism, and the re-winding of the picture strip or film by these methods not only devolves additional labor upon the machine operator, but in some instances delays the performance to the annoyance and 70 discomfiture of the audience. Again, the haste resorted to by the machine operators by these methods in quickly re-winding the film, often results in breaking or tearing the 75 picture strip. The present invention aims 80 to overcome these objections.

In carrying out the invention, the shaft commonly used in projecting apparatus for the accommodation of the empty spool or reel upon which the film is wound during the 85 picture projecting operation, is arranged to loosely hold a reel which may be filled with picture strip which has been previously exhibited, and a second shaft is arranged in near proximity to the first named shaft to 90 be driven thereby, and to contain an empty spool or reel for the reception of the picture strip contained upon the filled spool upon the first mentioned shaft. If desired, the 95 two shafts may be so intergeared that the second shaft will rotate more rapidly than the first shaft, to insure a complete re-winding of the film upon the filled spool regardless of the abbreviated length of the picture strip being exhibited.

More particularly, a casing 6 of suitable size, construction and shape is arranged for the support of a shaft 7, which shaft is adapted to support and impart rotary movement to the film receiving spool or reel 8; 105 the film being led to the spool 8 after it has been exhibited through the opening 9 in alinement therewith. A suitable bracket 10 may be secured upon the exterior of the casing 6 for the accommodation and support 110 of the shaft 7, a bushing 11 being arranged within the bracket 10, and the outer ex-

tremity of the shaft 7 has secured thereto a double pulley 12, having small and large belt receiving portions 13 and 14 respectively. The portion of the shaft 7 which 5 extends within the casing is preferably of such diameter as to receive the standard picture reels or spools, and a collar 15 may be secured to the shaft 7 by means of a screw 16, at the juncture of the smaller with 10 the larger portion of the shaft; a key 17 being arranged upon the collar to extend a short distance longitudinally of the shaft for engagement within the key way 18 common to the usual moving picture reel. From 15 this construction it is apparent that when the reel 8 is inserted upon the reduced portion of the shaft 7 with its key way engaged by the key 17, and the shaft rotated, the spool 8 will operate to receive and wind the 20 picture strip delivered from the picture projecting mechanism. It is apparent also that when desired the reel 8 may be readily withdrawn from the shaft.

The reduced portion of the shaft 7 is of 25 such length as to extend practically the entire width of the casing 6, and a bearing block 19 is arranged upon the door 20 adjacent the free end of the said shaft, the said block being provided with a suitable 30 bore 21 for the accommodation and support of the free end of the shaft 7 when the door is in closed position. The bearing block 19 is supported between a pair of brackets 22, set-screws 23 being threaded through the 35 said brackets and in engagement at their ends with the block 19, the arrangement providing means whereby the said block may be adjusted to properly aline the same with the end of the shaft 7. The door 20 is of 40 such size preferably as to cover the entire side of the casing, so that when swung to open position upon its hinges 24 the entire interior of the casing will be easy of access.

The spool or reel which is adapted to be 45 rewound by the use of the device, is indicated at 25, and is adapted, to be positioned upon the shaft 7 next to the reel 8 so as to rotate thereon. A spring clip 26 may be secured as at 27 to the end of the bearing 50 block 19 to engage and exert slight pressure upon the side of the reel 25 to prevent movement of the latter longitudinally of the shaft, and to hold the reel 25 snugly against the reel 8. Suitable spacing members or 55 washers 28 may be inserted between the reels, between the collar 15 and the reel 8, and between the spring member 26 and the reel 25.

A second shaft 29 is mounted similar in 60 manner to the shaft 7 adjacent the lower part of the casing and parallel with the said upper shaft. A suitable bearing block 30 is secured upon the interior of the casing 6 for the support of the shaft 29, the said 65 block having its bore provided with a bush-

ing 31 projecting beyond the casing to engage the inner face of a belt pulley 32 secured upon said shaft in alinement with the enlarged portion 14 of the member 12 upon the shaft 7. The opposite end of the shaft 70 29 projects beyond the inner extremity of the block 30, and is provided with a key 33 for engagement within the standard key way upon the picture reels. The arrangement is such that when a spool or reel 34 75 is inserted upon the inner end of the shaft 29, and the cap 35 applied to the shaft end, the spool or reel 34 will be in alinement with to receive picture strip or film from the spool or reel 25 mounted for rotation upon 80 the shaft 7. A belt 36 may be passed over the portion 14 of the member 12, and over the belt pulley 32 upon the shaft 29 for the purpose of imparting power from the first to the second shafts, and if desired this belt 35 may be crossed to drive the second shaft in a direction reverse from that of the first. It is also found desirable to have the belt pulley 32 smaller in diameter than the portion 14, in order that the shaft 29 may 90 rotate more rapidly than the shaft 7. Power is imparted to the shaft 7 by means of a belt 37 driven by suitable mechanism upon the projecting machine, the said belt passing over the portion 13 of the member 12. 95

In operation, an empty picture film reel or spool 8, is inserted upon the shaft 7 with its key way engaged by the key 17, and the end of the picture film to be exhibited is secured to the said reel. A reel of film which 100 it is desired to rewind, is inserted upon the shaft 7 and is free to rotate thereon. The end of the film contained upon the filled reel is connected to the empty reel 34 secured to rotate with the shaft 29, and the cap 35 is 105 secured over the end of the shaft 29 to prevent the reel becoming disengaged therefrom. The door 20 is then closed, and the bearing block 19 receives the free end of the shaft 7 within its bore. The spring element 110 26 upon closing of the door engages the reel containing the film to be re-wound and holds the same against lateral or wobbling movement upon the shaft 7. Upon operation of the picture projecting apparatus, rotary movement will be imparted through the belt 115 37 to the shaft 7, whereupon the film being exhibited will be wound upon the reel 8. Rotary movement is transmitted from the shaft 7 to the shaft 29 by means of the belt 36, and the film contained upon the reel 25 will be wound upon the reel 34 carried by the latter shaft. By reason of the more rapid rotation of the shaft 29, the film upon the reel 25 will be completely transferred in 120 correct display position to the reel 34 before the receiving reel 8 is filled. The spring element 26 by its engagement with the loose reel 25 acts as a brake for the latter to prevent racing of the same during the 125 130

operation of the device. By this arrangement it is obvious that the films may be rewound at the same time that other picture film is being exhibited, and by the construction shown, the various film reels may be quickly and easily removed or transferred from one shaft to the other.

While in the present instance I have illustrated and described my invention in what appears to me to be its most practical form, I am aware that the construction set forth is susceptible of various minor changes in form and details, and I reserve to myself the right to make such changes as I may deem practicable or desirable without departing from the spirit of the invention.

I claim.

1. In a device of the class described, a casing, a door hingedly connected to said casing, a pair of shafts mounted in spaced relation within said casing, a bracket upon the inner face of said door, a bearing block, a screw connecting said bearing block and said bracket, the said bearing block being adapted to engage and support one of said shafts when said door is in closed position, and means for rotating said shafts, substantially as described.

2. In a device of the class described, a casing, a door for said casing, a pair of shafts mounted in spaced relation within said casing, a bracket on said door, a bearing

block, a screw member connecting said bearing block and said bracket whereby the former may be adjusted, the said bearing block being adapted to engage and support one end of one of said shafts when said door is closed, a spring member secured to said bearing block and extending adjacent said shaft, and means for rotating said shafts, substantially as described.

3. In a device of the class described, a casing, a door hingedly connected to said casing and adapted to close one side thereof, a pair of shafts mounted in spaced parallel relation within said casing, a reel fixed to rotate with one of said shafts, a reel mounted for rotation upon said shaft, a bearing block upon said door adapted to engage the end of said shaft when said door is closed, a spring member secured to said bearing block and adapted to engage said loose reel when said door is closed, a reel fixed to the other of said shafts and in alignment with said loose reel, a cap for engagement over the end of said second shaft, and means for rotating said shaft, substantially as described.

In testimony whereof I affix my signature in the presence of two witnesses.

WILLIAM HEINZE.
